APPARATUS FOR HEAT TREATING

John Lindon Pearson, Norton-on-Tees, England,
assignor to Imperial Chemical Industries Limited,
a corporation of Great Britain

Original application December 5, 1934, Serial No.
756,185. Divided and this application July 15,
1938, Serial No. 219,450. In Great Britain
December 8, 1933

15 Claims.

(Cl. 266—5)

This invention relates generally to apparatus for heat treating and it relates more particularly to apparatus for heat treating metals in a neutral or non-oxidizing atmosphere to prevent scaling or oxidation of the surfaces of the metals being treated or annealed.

Considerable attention has been paid during recent years to this art, and more particularly to that branch known as bright annealing, which 10 offers many advantages over the older methods of heat treatment in oxidizing atmospheres followed by pickling or descaling. The main factor which has prevented the wider adoption of the use of neutral or reducing atmospheres in connection with the heat treatment of metals and 15 their products has been the cost of the gas necessary to produce this atmosphere. This is especially the case with continuous heat treating or annealing furnaces and with relatively cheap 20 metal products.

In continuous furnaces using protective atmospheres in which the articles to be treated move through the furnace in a continuous stream, it is not possible to seal the ends against 25 leakage of protective atmosphere and infiltration of air. Hitherto the former has been allowed to escape from the ends at a rate sufficient to prevent air leaking into the furnace up to any point where the temperature is such that oxidation 30 would take place. Consequently, the quantity of gas required becomes so great in the case of large annealing furnaces that in many cases the process is considered to be uneconomical with known 35 methods.

In batch furnaces during the actual period of heating, there is generally no difficulty with air contamination, since they can be effectively sealed from the outside atmosphere. However, when a batch furnace is closed after being 40 charged with articles to be heat treated, it contains air which has entered during the charging operation and its oxygen has to be removed before heat treatment can be commenced. Up to the present this removal has been effected by 45 sweeping it out into the outside atmosphere by a stream of protective gases or by a special gas such as carbon dioxide, which is in turn swept out by a stream of protective gases. Although a considerable proportion of the air is thus removed 50 en masse, mixing between the protective gas or special gas and the air takes place to a substantial extent, with the result that an amount of the protective gas or special gas many times that of the air, is blown out into the outside atmosphere 55

and wasted before the furnace is sufficiently free from oxygen for heat treatment to commence.

An object of the present invention is to reduce the consumption of protective atmosphere in both continuous and batch furnaces for the thermal treatment of metals and their products in a protective atmosphere and to provide a furnace in which heat treatment, particularly bright annealing, of metal articles may be conducted with maximum efficiency and minimum expense.

Other objects and novel features and advantages of the invention will become apparent from the following description taken in connection with the accompanying drawings which illustrate one practical form of apparatus embodying the 15 invention, it being understood that the description of this specific embodiment is merely illustrative and not restrictive and that various changes in arrangement and details of construction can be made without departing from the 20 spirit and scope of the invention as set out in the appended claims.

According to the present invention, the consumption of protective atmosphere is decreased in the case of continuous furnaces by recovering 25 at least in part the protective atmosphere leaving the heat treatment zone of the furnace, and utilizing the adventitious oxygen, present in the protective atmosphere through air infiltration from outside the furnace, for the production of 30 further amounts of protective atmosphere by combustion with combustible gas, the resulting protective atmosphere being recirculated to the furnace, and in the case of batch furnaces, by driving the air left in the furnace after charging 35 with the articles to be heat treated, at least in part into the protective atmosphere circulating system, and utilizing it for the production of further quantities of protective atmosphere by combustion with combustible gas.

In the case of furnaces of the continuous type, the withdrawal of the gases is most conveniently effected by means of one or more ports in the inlet and outlet ducts where the temperature has fallen sufficiently low that the materials being 40 bright annealed may be safely exposed to an atmosphere containing oxygen.

The removal of the oxygen from the withdrawn 45 gases is carried out in apparatus (hereinafter referred to as a burner) in which the gases withdrawn from the furnace are heated (in the presence of a catalyst for at least a portion of the time), in admixture with butane, natural gas, decomposed ammonia or the like, or their products 50 of combustion, with a restricted amount of oxy- 55

gen-containing gas, and for a portion, at least, of the period of heating, in the presence of a catalyst, whereby oxygen contained in the gases withdrawn from the furnace is removed.

5 The gases leaving the burner may be reduced to the temperature required in known forms of coolers, and usually it is desirable to provide means for separating water from the gases before they are returned to the furnace.

10 In order to obtain reasonably smooth operation of the burner, it is desirable to ensure that the gases which are sent to it have a fairly uniform oxygen content. This may be achieved in the case of continuous furnaces by providing a number of curtains of soft material such as asbestos cloth in the inlet and discharge ducts which control the ingress of air and egress of reducing gases through the openings, even when varying sizes of articles are passing in and out of the furnace. It is also an advantage to provide a capacity vessel in the pipe line leading from the furnace back to the regenerative burner. Furthermore the amount of oxygen in the protective gas from the furnace may not be sufficient when 15 burnt with ammonia, natural gas, or the like, or their partial combustion products, to render the burner autothermal. In this case autothermicity may be obtained by adding further oxygen, e. g., from the outside atmosphere, to the mixture of 20 contaminated protective gas with ammonia, natural gas or the like, or their partial combustion products, and burning it in the burner.

The gas or gases withdrawn from the furnace may contain objectionable constituents arising 35 from the lubricants used in cold working as for example in tube drawing, or wire drawing, and this objectionable constituent may be removed either before or after the regenerative burner by means of suitable scrubbing or purification 40 means. Thus for example, unless the tubes or wire are degreased before bright annealing, the gas withdrawn from the furnace may contain hydrogen sulphide, and this can be removed either by passing the gas through the ordinary 45 type of iron oxide box or by scrubbing the gas in a small tower or washer by means of a solution of sodium carbonate or other liquor.

The application of the present invention to heat treating or annealing furnaces of the continuous type will now be described with reference 50 to the accompanying drawings, in which Figure 1 is a diagrammatic elevation of an annealing furnace showing the gas circulation system, and Figure 2 is a graph showing the effect of different 55 kinds of material when used for screening the inlet and outlet passages of the furnace.

Referring to Figure 1, the neutral or reducing gas, consisting for example of nitrogen or nitrogen containing a small percentage of hydrogen, is fed into the tunnel-like annealing furnace 1 through one or more ports 2 situated in the wall 60 of the furnace where the cooling chamber 3 adjoins the heating chamber 4. The rate at which the gas is introduced is measured by means of the flowmeter 5, and is sufficient to produce in the inlet and outlet ducts 6 and 7 for the articles being annealed a velocity such that ingress of oxygen from the outside atmosphere is prevented from reaching the metal articles before they are 65 cooled to a safe temperature.

A band conveyor 8 carries the metal objects to be heat treated, e. g., tubes, bars, or wire, through the furnace, and flexible curtains 9 and 10 are arranged to screen the inlet and outlet 75 ducts at their outer ends. Gas exit ports 11 and

12 are provided in the gas ducts 6 and 7. Connections for manometers 13 and 14 are provided to enable the pressure of the gas at these points to be measured with a view to controlling the flow of gas by means of valves 15 and 16. The ends of the furnace are fitted with vertical sliding doors 17 and 18, to which are attached inclined baffles 19 and 20.

The gas which is withdrawn from the furnace through ports 11 and 12 passes via pipes 21 and 10 22 to a common main 23 leading to a capacity vessel 24 and a suction fan 25. The fan delivers the gas through a valve 26 to a heat exchanger 27. The gas enters the coil 28, in which it is preheated, and emerges by the pipe 29 leading to 15 a catalyst combustion chamber 30.

The gas issuing from the pipe 29 is mixed in the chamber 30 with additional gas entering by pipe 31. This additional gas is derived from the decomposition of ammonia which is introduced 20 by pipe 32 into a coil 33 in the vessel 34 adjoining the catalyst chamber 30. The coil 33 is heated in a manner to be explained and the ammonia is partially or completely decomposed during its 25 passage through the coil. From the coil the gas passes through pipe 35 to a burner 36 where it is mixed with air extracted from near the ends of the furnace 1 by means of the fan 37, the gas 30 delivery rate of which is measured by flowmeter 48. This air contains a certain amount of valuable gas which would otherwise escape from the furnace and which is recovered by the arrangement shown. However, this arrangement is optional and it is possible to operate the burner with ordinary air. The gases issuing from the 35 burner are ignited and burn in the space 38a within coil 33, thus heating the latter and causing the decomposition of the ammonia passing through the same.

The combustion products pass through pipe 31 40 and mix with the gas issuing from pipe 29 as previously described. The mixed gases then pass over the catalyst gauzes 38, 39 and 40 in succession and their oxygen content is substantially 45 eliminated. The gauze 38 is made of an iron alloy containing 18% chromium, 8% nickel, 1% tungsten and 1% vanadium; the gauze 39 is made of copper and the gauze 40 is made of palladium.

The resulting gases pass via pipe 41 into the heat exchanger 27 and are caused to sweep over 50 the coil 28 by the baffle 42 which prevents their passing straight through the space surrounded by the coil. The gases then pass by pipe 43 to a cooler 44 and thence to a drier 45 and a capacity vessel 46 before being returned to the furnace by 55 pipe 47 leading to the port 2.

During the starting up period all the neutral or reducing gas may be allowed to pass out through the ends of the ducts 6 and 7 until the atmosphere in the furnace is substantially free of oxygen. The recirculating fan 25 is now started and the valves 15 and 16 adjusted until the rate, measured by the flowmeter 51 at which gas is withdrawn from the furnace, is about 90% of the rate of introduction of gas into the furnace via the pipe 47. About 5% of the gas introduced into the furnace is passed out to atmosphere through each of the inlet and outlet ducts, and this escaping gas together with the curtains 9, 65 70 10 and baffles 19, 20, minimizes the entrance of oxygen due to diffusion and/or natural draughts. By means of the sampling points 49, 50 the composition of the gases leaving and passing to the furnace may be tested and the percentage of gases

withdrawn adjusted to give the correct atmosphere in the furnace.

In the case of a small annealing furnace with inlet and outlet ducts of 0.44 square foot cross sectional area and a total furnace length of 10 feet, a gas mixture consisting of 95% nitrogen and 5% hydrogen by volume was fed into the furnace at the rate of 230 cubic feet per hour. The rate at which gas was withdrawn from the furnace by the recirculating fan was about 218 cubic feet per hour, and the rate at which make-up gas was supplied was 12 cubic feet per hour. With an oxygen content of 2 per cent by volume in the withdrawn gas, a total ammonia rate of 9.3 cubic feet per hour was required to consume this oxygen and also to produce a make-up gas containing 10% hydrogen by volume. The amount of air provided by the air blower for the make-up gas was 12.5 cubic feet per hour. This air or mixture of air and gas was taken from points near the furnace ends external to the curtains 9, 10 in order to minimize the effect of eddy currents or draughts of air in causing contamination of the furnace gas with oxygen.

Under these conditions and with inlet and outlet passages without curtains or inclined baffles fitted to the doors, the degree of oxygen contamination is indicated by the curve A in Figure 2. Curve B in Figure 2 shows the improvement obtained by fitting the inclined baffles to the doors. Curve C in Figure 2 shows the effect of fitting divided curtains in addition to the inclined baffles. Curve D in Figure 2 shows the effect of substituting string curtains for the divided curtains, the inclined baffles being retained. Objects of various sizes could be passed in and out of the annealing furnace and no variation in the degree of oxygen contamination could be detected.

This application is a division of my copending application Serial No. 756,185 filed December 5, 1934, now Patent 2,146,760, dated Feb. 14, 1939.

What is claimed is:

1. Apparatus for the heat treatment of metals in a non-oxidizing protective atmosphere comprising a furnace having a substantially unobstructed heat treatment chamber for articles to be treated, and a closed circulating system connected to said chamber and including means for supplying a non-oxidizing gas to said chamber, means for withdrawing, from said chamber, gas contaminated with free oxygen, means for uniting with said withdrawn gas a supply of reducing gas at least sufficient to combine with the oxygen of the oxygen-carrying withdrawn gas, means outside the heat treatment chamber for heating the mixture thereby produced to bring about a chemical combination of the oxygen and the reducing gas to form a substantially oxygen-free non-oxidizing gas, and means for circulating the resultant oxygen-free non-oxidizing gas back to said chamber.

2. Apparatus for the bright annealing of metals in a non-oxidizing atmosphere comprising a furnace having a substantially unobstructed heat treatment chamber for metals to be treated and a closed circulating system connected to said chamber for circulating a non-oxidizing gas into, through and out of said chamber whereby contaminating oxygen in the chamber is carried out with the outgoing portion of said circulating gas, said circulating system including a catalytic combustion chamber, outside the heat treatment chamber, into which said oxygen-contaminated gas passes, means for introducing a supply of

reducing gas into said combustion chamber to form therein a mixture of reducing gas and oxygen-contaminated gas, means for heating the mixture to cause the chemical combustion of substantially all of the oxygen in it with reducing gas, and means for circulating the resultant oxygen-free non-oxidizing gas back to said heat treatment chamber, said circulating system including an unobstructed capacity vessel between the heat treatment chamber and said combustion chamber.

3. Apparatus for the bright annealing of metals in a non-oxidizing atmosphere comprising a substantially unobstructed heat treatment chamber for metals to be treated, said chamber having inlet and outlet ducts for the continuous unobstructed passage of metals into, through and out of said chamber, means for conveying metals through said chamber, and a closed circulating system connected to said chamber for circulating a non-oxidizing gas into, through and out of said chamber whereby contaminating oxygen in the chamber is carried out with the outgoing portion of said circulating gas, said circulating system including means for supplying a non-oxidizing gas under pressure to said chamber intermediate said inlet and outlet ducts to create a flow of non-oxidizing gas outwardly through both of said inlet and outlet ducts to resist inflow of air into said chamber through said ducts, means for withdrawing gas contaminated with oxygen from the inlet and outlet ducts of said chamber, means for uniting with said withdrawn gas a supply of reducing gas at least sufficient to combine with the oxygen of the oxygen-carrying withdrawn gas, means outside the heat treatment chamber for heating the mixture to cause the chemical combination of substantially all of the oxygen in it with reducing gas, and means for circulating the resultant oxygen-free non-oxidizing gas back to said chamber.

4. Apparatus as set out in claim 3, in which flexible curtains are provided to screen the inlet and outlet ducts of said heat treatment chamber.

5. Apparatus as set out in claim 3, in which the inlet and outlet ducts are provided with sliding doors carrying inclined baffles adapted to restrict the entrance and escape of gases through said ducts.

6. Apparatus for the bright thermal treatment of metals in a non-oxidizing protective atmosphere comprising a substantially unobstructed heat treatment chamber for metals to be treated, said chamber having inlet and outlet ducts for the continuous unobstructed passage of metals into, through and out of said chamber, means for conveying metals through said chamber, means for supplying said chamber with a continuous stream of non-oxidizing gas forming said protective atmosphere which flows outwardly along both of said inlet and outlet ducts and is there subject to contamination with air, means for withdrawing gas contaminated with air from said inlet and outlet ducts, means for mixing the withdrawn gas with an amount of combustible gas at least sufficient to combine with the entire oxygen content of the air-carrying withdrawn gas, means outside the heat treatment chamber for subjecting the mixture to a temperature sufficient to cause the chemical combination of substantially all of the oxygen and the combustible gas, and means for returning the resultant oxygen-free non-oxidizing gas to the chamber intermediate the inlet and outlet ducts.

7. Apparatus for the bright annealing of metals in a non-oxidizing protective atmosphere comprising a substantially unobstructed heat treatment chamber for metals to be treated, said chamber having inlet and outlet ducts for the continuous unobstructed passage of metals into, through and out of said chamber, means for conveying metals through said chamber, means for supplying said chamber with a continuous stream of non-oxidizing gas forming said protective atmosphere which flows outwardly along both of said inlet and outlet ducts and is thereby subject to contamination with air, a combustion chamber, outside said heat treatment chamber, means, including an unobstructed capacity vessel, for withdrawing gas contaminated with air from said inlet and outlet ducts and introducing it into said combustion chamber, means for introducing a supply of combustible gas into said combustion chamber to form therein a mixture of combustible gas and oxygen-contaminated gas, means for combusting the oxygen content of said mixture to form an oxygen-free non-oxidizing gas, and means for returning the resultant oxygen-free non-oxidizing gas to the heat treatment chamber intermediate the inlet and outlet ducts.

8. Apparatus for the bright annealing of metals in a non-oxidizing atmosphere comprising a substantially unobstructed heat treatment chamber for metals to be treated, said chamber having inlet and outlet ducts for the continuous unobstructed passage of metals into, through and out of said chamber, means for conveying metal through said chamber, and a closed gas circulating system connected to said chamber for circulating a non-oxidizing gas into, through and out of said chamber whereby contaminating oxygen in the chamber is carried out with the outgoing portion of said circulating gas, said circulating system including means for supplying a non-oxidizing gas under pressure to said chamber intermediate said inlet and outlet ducts to create a flow of non-oxidizing gas outwardly through both of said inlet and outlet ducts to resist inflow of air into said chamber through said ducts, a combustion chamber, outside said heat treatment chamber, means for withdrawing gas contaminated with oxygen from the inlet and outlet ducts of said heat treatment chamber and introducing it into said combustion chamber, a burner, means for supplying said burner with combustible gas, means for conducting hot combustion products from said burner into said combustion chamber to form therein a mixture of said combustion products with said oxygen-contaminated withdrawn gas and cause the chemical combination of substantially all of the oxygen in said mixture with the hot reducing constituents thereof, and means for returning the resultant oxygen-free non-oxidizing gas to the heat-treatment chamber intermediate its ends.

9. Apparatus as set out in claim 8, in which a catalyst is provided in said combustion chamber to promote chemical combination of the gases therein.

10. Apparatus as set out in claim 8, including a heat exchanger whereby the hot gases from said combustion chamber will heat the oxygen-contaminated withdrawn gas flowing to said combustion chamber.

11. Apparatus as set out in claim 8, including means for withdrawing air from near the outer ends of the inlet and outlet ducts of said heat treatment chamber and for supplying said air,

containing a proportion of non-oxidizing gas escaping through said ducts from said heat treatment chamber, to said burner to provide limited combustion of the combustible gas supplied to said burner.

12. Apparatus for the bright annealing of metals in a non-oxidizing atmosphere comprising a heat treatment chamber for metals to be treated, said chamber having inlet and outlet ducts for the continuous passage of metals into, through and out of said chamber, means for conveying metals through said chamber, and a closed gas circulating system connected to said chamber for circulating a non-oxidizing gas into, through and out of said chamber whereby contaminating oxygen in the chamber is carried out with the outgoing portion of said circulating gas, said circulating system including means for supplying a non-oxidizing gas to said chamber, a catalytic combustion chamber outside of said heat treatment chamber, means for withdrawing gas contaminated with oxygen from the inlet and outlet ducts of said heat treatment chamber and introducing it into said combustion chamber, a burner, means for supplying said burner with combustible gas, means for supplying said burner with a limited amount of air for partial combustion of said combustible gas, a burner chamber into which said burner discharges hot combustion products, said burner chamber being provided with heat-exchange means whereby said combustible gas is heated to decomposing temperature prior to passage to said burner, means for conducting the hot combustion products from said burner chamber to said combustion chamber to form therein a mixture of said combustion products with said oxygen-contaminated withdrawn gas whereby the oxygen in said mixture will chemically combine with the reducing constituents thereof, and means for returning the resultant non-oxidizing gas to the heat treatment chamber intermediate its ends.

13. An apparatus for the bright annealing of metals comprising a furnace having inlet and outlet ducts at its ends, flexible curtains to screen said inlet and outlet ducts, for the articles to be treated, at least one gas exit port in each of the ducts, at least one gas inlet port in the furnace, an external purifier adapted to remove free oxygen from gas passed therethrough, and means including gas pipe lines connected to said ports for circulating protective gas through the furnace, through the purifier and back to the furnace.

14. An apparatus for the bright annealing of metals comprising a furnace having inlet and outlet ducts at its ends, for the articles to be treated, at least one gas exit port in each of the ducts, at least one gas inlet port in the furnace, an external purifier adapted to remove free oxygen from gas passed therethrough, and means including gas pipe lines connected to said ports for circulating protective gas through the furnace, through the purifier and back to the furnace, the ends of the furnace being fitted with sliding doors carrying inclined baffles adapted to restrict the transfer of gas through the inlet and outlet passages.

15. Apparatus for the heat treatment of metals in a non-oxidizing protective atmosphere comprising a furnace having a closed heat treatment chamber for articles to be treated in batches, and a closed circulating system connected to said chamber and including means for supplying a non-oxidizing gas to said chamber, means

for withdrawing, from said chamber, gas contaminated with free oxygen, means for uniting with said withdrawn gas a supply of reducing gas at least sufficient to combine with the oxygen of the oxygen-carrying withdrawn gas, means outside the heat treatment chamber for heating the mixture thereby produced to bring about

a chemical combination of the oxygen and the reducing gas to form a substantially oxygen-free non-oxidizing gas, and means for circulating the resultant oxygen-free non-oxidizing gas back to said chamber.
